[57] **ABSTRACT**

New compounds represented by the formula:

wherein x and y are each integers from 1 to 17, the sum of $x + y$ being from 12 to 18; R is hydrogen or methyl; and M is sodium or potassium, are useful surfactants and lime soap dispersants, which provide, in admixture with natural soaps, excellent cleansing compositions having reduced tendency to deposit precipitates in hard water.

4 Claims, No Drawings

ALKYL VICINAL HYDROXY ALKOXY ETHER MALEATE COMPOUNDS

BACKGROUND OF THE INVENTION

This invention relates to novel compounds and to improved soap compositions containing such compounds. More particularly, the invention relates to alkyl vicinal hydroxy alkoxy ether maleates and to natural soap formulations containing such compounds and exhibiting reduced tendency to deposit precipitates in hard water.

The excellent performance characteristics of soaps derived from animal fats and vegetable oils, e.g., lauric, myristic, palmitic, stearic, tallow and coconut oil acid soaps are well-known. However, when such soaps are employed in hard water, (i.e., water containing substantial quantities of alkaline earth metal ions-particularly calcium or magnesium) they interact with the anionic constituents of such water to form insoluble precipitates which tend to deposit on washing vessels and items being washed. Such undesirable effects are exemplified by such phenomena as "the ring around the tub" which frequently demarcates the water line of washing vessels utilized in geographical localities having hard water supplies.

Although deposition of precipitates by such compositions can be inhibited by use of sequestrants to "soften" the water, such sequestrants are inert compounds which do not contribute to the cleansing power of the compositions in soft water. Further, such additives sometimes impair physical characteristics of bar soap compositions in terms of hardness, gloss, solubility, etc., and therefore, are not desired for use therein.

SUMMARY OF THE INVENTION

It is an object of this invention to provide novel compounds and improved soap compositions based on such compounds.

The novel compounds of this invention are alkyl vicinal hydroxy alkoxy ether maleates as hereinafter described. Basically, the improved soap compositions of this invention comprise natural soaps in combination with minor amounts of such novel compounds.

The invention will be understood from the following description of the preferred embodiments.

DESCRIPTION OF THE PREFERRED EMBODIMENTS

The alkyl vicinal hydroxy alkoxy ether maleates of 50 this invention are represented by the formula:

wherein x and y are each integers from 1 to 17, the sum of $x + y$ being from 12 to 18; z is an integer from 1 to 3; R is hydrogen or methyl; and M is sodium or potassium. These compounds are effective both as surfactants and for use as lime soap dispersants in natural soap compositions of the type hereinafter described. For optimum performance in these applications, compounds wherein the sum of $x + y$ is from 14 to 16, z is 1, and R is hydrogen are preferred.

The compounds of this invention can be prepared by various procedures. For example, straight chain internal olefins such as obtained by catalytic dehydrogenation of paraffins can be epoxidized by reaction with peracetic acid, and the epoxide reacted with appropriate mono- or poly-ethylene or propylene glycols in the presence of a Lewis acid catalyst to yield an alkyl vicinal mono- or poly-alkoxylate which is reacted with maleic anhydride and neutralized with a sodium or potassium base to yield the compounds of this invention.

The foregoing compounds are excellent surfactants and, additionally, are found to inhibit precipitate deposition of natural soaps in hard water.

The soap compositions of this invention comprise a soap derived from natural products, (hereinafter referred to in the specification and claims as natural soaps) in combination with the alkyl vicinal hydroxy alkoxy ether maleates described above.

Any of the well-known natural soaps conventionally employed is soap bars and/or powders, can be utilized in the compositions of this invention. Such natural soaps include sodium and potassium salts of acids obtained by saponification of animal fats and vegetable oils, for example, lauric, myristic, palmitic, stearic, tallow and coconut oil acids and mixtures thereof. As is known to those skilled in the art, the selection of natural soap constituents is based on the physical and performance characteristics desired as well as cost and availability of the natural products from which the soaps are derived.

The compositions of this invention may contain a single hydroxy alkoxy ether maleate; a mixture of position isomers wherein the hydroxy and alkoxy ether maleate substituents are attached at various isomeric positions, e.g., 2,3 or 3,4, or 4,5 etc.; a mixture of hydroxy alkoxy ether maleates of various alkyl chain lengths, i.e., a homolog mix, or; homolog mixes wherein individual homologs comprise a mixture of position isomers. The compositions of this invention must contain at least 12 percent by weight of the hydroxy alkoxy ether maleate (based on the combined weight of the maleate and natural soap) to effectively inhibit precipitate deposition. The use of greater than 25 percent by weight maleate does not provide bar soaps of acceptable physical characteristics. A maleate content of from 15 to 20 percent by weight is particularly preferred.

In addition to the foregoing essential components, the compositions of this invention may contain minor amounts of perfumes, dyes, abrasives, antiperspirants, germicides or other additives conventionally employed in soap compositions. The invention is further illustrated by the following examples, wherein all percentages are by weight unless otherwise indicated.

EXAMPLE I - VI

Alkyl vicinal hydroxy alkoxy ether maleates are prepared by reacting internal olefins as shown in Table 1 below with peracetic acid which is added dropwise to the olefin, the reaction mixture being maintained at a temperature of about 50° C via an ice bath. The epoxide formed is separated as a top layer from the reaction mixture, washed with aqueous Na_2CO_3 and water until the wash water is neutral and dried by contact with Na_2SO_4 . The epoxide is then reacted with mono- or

polyethylene or propylene glycols as shown in Table I at about 90° C, and the product reacted with maleic anhydride. The acids produced are neutralized with a 10 percent by weight NaOH solution at 30° C to yield the maleates indicated.

TABLE 1

Example	Vicinal Internal Olefin	Glycol	Vicinal Hydroxy Alkoxy Ether Maleate
I	tetra-decene	ethylene glycol	tetradecyl hydroxy monoethoxy ether sodium maleate
II	hexa-decene	ethylene glycol	hexadecyl hydroxy monoethoxy ether sodium maleate
III	hexa-decene	propylene glycol	hexadecyl hydroxy monopropoxy ether sodium maleate
IV	octa-decene	ethylene glycol	octadecyl hydroxy monoethoxy ether sodium maleate
V	octa-decene	diethyl-ene glycol	octadecyl hydroxy diethoxy ether sodium maleate
VI	eicosene	triethyl-ene glycol	eicosyl hydroxy triethoxy ether sodium maleate

EXAMPLES VII - XIII

Soap bars are prepared by blending the ingredients shown in Table 2 below (percentages are based on dry weight) with about 18 percent by weight water and pressing the blended mass in a 2 $\frac{1}{4}$ inch diameter die at about ten thousand pounds per square inch. Physical properties are reported in the table. Deposition properties are determined by immersing black tile plates in 1 percent solutions of each composition in water containing 200 parts per million by weight calcium; removing, draining and drying the plates at ambient temperatures; and observing the amount of precipitate deposited thereon. Relative precipitate deposition is reported in the Table.

TABLE 2

Example	Hydroxy Alkoxy Maleate	Natural Soaps	Physical Properties	Precipitate Deposition
VII	none	20% coconut oil soap 80% tallow soap	good	high
VIII	12% product of Ex. II	88% (20% coconut oil soap 80% tallow soap)	good	low
IX	16% product	84%	good	negligible

		of Ex. II (20% coconut oil soap 80% tallow soap)		
5	X	25% product 75% of Ex. VI (20% coconut oil soap 80% tallow soap)	good	negligible
10	XI	15% product 85% of Ex. I (20% coconut oil soap 80 % tallow soap)	good	negligible
15	XII	20% product 80% of Ex. III (20% coconut oil soap 80% tallow soap)	good	negligible
	XIII	20% of 50:50 80% weight mix (20% coconut of products oil soap of examples 80% tallow IV & V soap)	good	negligible

20 Examples VIII – XIII above representing compositions formulated according to this invention are seen to provide significant advantages as compared to formulations containing no maleate (Example VII).

What is claimed is:

25 1. Alkyl vicinal hydroxy alkoxy ether maleates represented by the formula .

35 wherein x and y are each integers from 1 to 17, the sum of $x + y$ being from 12 to 18, z is an integer from 1 to 3, R is selected from the group consisting of hydrogen and methyl and M is selected from the group consisting of sodium and potassium.

2. Alkyl vicinal hydroxy alkoxy ether maleates according to claim 1 wherein R is hydrogen.

3. Alkyl vicinal hydroxy alkoxy ether maleates according to claim 2 wherein z is 1.

4. Alkyl vicinal hydroxy alkoxy ether maleates according to claim 3 wherein the sum of $x + y$ is from 14 to 16.
